UNITED STATES PATENT OFFICE.

LOUIS STEINBERGER, OF NEW YORK, N. Y.

STRAIN-INSULATOR.

974,610.

Specification of Letters Patent.

Patented Nov. 1, 1910.

Application filed June 17, 1910. Serial No. 567,418.

To all whom it may concern:

Be it known that I, LOUIS STEINBERGER, a citizen of the United States, and a resident of the city of New York, borough of Brooklyn, in the county of Kings and State of New York, have invented a new and Improved Strain-Insulator, of which the following is a full, clear, and exact description.

My invention relates to strain insulators admitting of general use and also of various special uses in connection with wireless towers, commercial cables, and in practically all relations where great insulating strength is to be combined with great mechanical strength.

Among the objects sought to be accomplished by my invention are the following: I. To increase the protection given to the body portion of the insulator in order to prevent the leakage of the current due to moisture; II. To specially insulate the metallic suspension members within the body member; III. To give the metallic suspension members such form as will greatly increase the mechanical strength of the insulator; IV. To protect the ends of the body portion where subjected to undue mechanical strains by inclosing them in metallic caps; V. To secure the aforesaid metallic caps toward each other and thereby cause them to bind hard upon the body member; VI. To protect the lowermost of said caps from the action of moisture; VII. To render various internal parts of the insulator readily accessible; VIII. To give the metallic suspension members such configuration as will confer upon them a mechanical strength without impairing their insulation; IX. To provide one of the metallic suspension members with an anchor disk possessing a maximum of mechanical strength for a given weight of material; X. To give the anchor disk just mentioned a peculiar shape, in order to facilitate its insulation without impairing its mechanical strength; XI. To provide fillings of improved form for various cavities and recesses within the body portion; XII. To improve generally the construction and efficiency of various parts of the insulator.

Reference is to be had to the accompanying drawings forming a part of this specification, in which similar characters of reference indicate corresponding parts in all the figures.

Figure 1 is a substantially central vertical section through a strain insulator, made in accordance with my invention; Fig. 2 is a horizontal section on the line 2—2 of Fig. 1, looking in the direction of the arrow; Fig. 3 is a horizontal section on the line 3—3 of Fig. 1, looking in the direction of the arrow; Fig. 4 is a detail showing in perspective the anchor ring; and Fig. 5 is a detail showing in perspective the upper tension member carrying the anchor plate associated with it.

A body member 6 is made of insulating material, preferably electrose or hard rubber, and is provided with a central frusto-conical portion 7 integral with it. Encircling this portion 7 and extending considerably below the same is a petticoat 8. A hood 9 encircles this petticoat and is integral with it, as well as with the body member 6. The slant of the hood 9 is the same as that of the body member 6, these two parts presenting from the outside the appearance of a single cone frustum. The upper portion of the body member 6 is provided with a neck 10 having generally an annular form. The body member 6 is further provided with an annular recess 11, the upper portion of which bounds the inner surface of the annular neck 10. An anchor ring is shown at 12 and is provided with bolt holes 12^a and with a large central opening 12^b. Two bolts 13 provided with heads 14 are adapted to extend through the bolt holes 12^a and are fitted with nuts 15, being threaded for this purpose. A larger bolt 16 is provided adjacent to one of its ends with a thread 17 and at its opposite end with an anchor disk 18, the latter being provided with large apertures 19, each having a circular outline, as indicated in Figs. 3 and 5. The anchor disk 18 is provided with a rounded thickened portion 20 (see Fig. 1) integral with it and serving to strengthen it. The lower end of the body member 7 is provided with a central axial recess containing a filling 21 which may be of softer insulating material than said body member.

The annular recess 11 contains a similar filling 21^a of soft insulating material. A metallic cap 22 provided with an annular flange 23 is fitted upon the lower end of the frusto-conical portion 7 and is provided with an eye 24. The bolts 13 extend through openings in the cap 22 and the nuts 15 hold

this cap rigidly in position, causing it to bind against the lower end of the frustoconical portion 7 and also against the lower end of the filling 21. The body portion 6 5 is provided centrally with a tubular member 25 integral with it and forming the inner boundary of the annular passage 11.

At 26 is a metallic cap which is provided with an annular flange 27, the latter fitting 10 neatly around the neck 10. An eye 29 is provided with a socket 28 which is threaded internally and fitted upon the threaded portion 17 of the bolt 16. At 18^a is a fiber washer against which the pressure of the 15 anchor disk 18 is exerted. At 13^a is another fiber washer which in this instance meets the anchor ring 12 and sustains the pressure due to the pull of the bolts 13.

In assembling the various parts, the body 20 member 6 is first inverted and the bolt 16 carrying the anchor disk 18 is dropped into it so that the threaded portion 17 of the bolt 16 protrudes. The bolt 16 is temporarily held in this position and the body member 25 is now inverted, the anchor ring 12 and washer 13^a being now dropped into the annular recess 11 and the bolts 13 being threaded through the openings in the anchor ring and washer. The fillings 21, 21^a are next 30 placed in position, which may be done by melting the fillings and pouring them in, or by merely fitting them in by hand if the materials are hard and cold. The caps 22, 26 are next placed in position, the cap 22 being 35 held by pressure of the nuts 15 and the cap 26 being secured by pressure of the socket 28.

It will be noted that the annular flange 27 being directed downwardly when the parts are in the position indicated in Fig. 1, any 40 water or moisture falling upon the cap 26 is readily carried off and must follow the inclination of the body member 6 and hood 9, finally making its escape from the outer and lower edge of this hood. It will also be 45 noted that all parts immediately connected with the bolts 13 are sheltered from the action of moisture and are completely protected by the petticoat 8, the upper portion of this petticoat being in turn protected by 50 the hood 9.

The operation of my device is not greatly different from that of other strain insulators of my invention.

The eye 29 is connected to a cable, a wire 55 or a suspension member of any kind, or even to another insulator, and the eye 24 being similarly connected, the device will resist a considerable mechanical strain and may be subjected to a very high voltage 60 without injuring any of the parts.

I do not limit myself to any particular material to be used in the construction of this insulator or any of its parts. Neither do I limit myself to the precise arrange-

ment shown for the various mechanical features, nor to any special proportions or shapes for the parts except as specified in my claims.

Having thus described my invention, I claim as new and desire to secure by Letters Patent:

1. A strain insulator, comprising a body member provided with a recess and with an opening merging into said recess, a single metallic tension member extending through 75 said opening and provided with an anchor disk located within said recess, a plurality of metallic tension members disposed upon opposite sides of said single metallic tension member, and means for anchoring said plurality of metallic tension members relatively to said body member.

2. A strain insulator, comprising a body member provided with a tubular portion integral therewith, and further provided with 85 an annular recess bounding said tubular portion, a metallic ring disposed within said annular recess, metallic tension members extending through portions of said metallic ring and exerting tension upon said body 90 member in one direction, and means for exerting tension upon said body member in the opposite direction.

3. A strain insulator, comprising a body member provided with a tubular portion integral therewith and further provided with an annular recess concentric to and forming a boundary for said tubular portion, a metallic ring mounted within said annular recess and provided with bolt holes, a plurality 100 of bolts extending through said bolt holes for exerting tension upon said body member in one direction, and a single bolt provided with a portion engaging said body member for exerting tension thereupon in the opposite direction.

4. A strain insulator, comprising a body member provided with a tubular portion integral therewith and further provided with a recess extending toward but not reaching 110 said tubular portion, a single bolt extending through said tubular portion and provided with an anchor disk disposed within said recess for exerting tension upon said body member in one direction, a filling disposed 115 within said recess, a cap covering said filling, and tension members extending through said cap and provided with means for exerting tension upon said body member in a direction contrary to that exerted by said 120 single bolt.

5. A strain insulator, comprising a body member provided with a tubular portion integral therewith, and further provided with an annular recess concentric to said tubular 125 portion, an anchor ring and a washer fitted into said annular recess, bolts extending through portions of said anchor ring and

also through portions of said body member, a metallic cap engaging said body member, means connected with said bolts for exerting pressure upon said cap, and a tension member connected with said body portion and extending in a direction opposite to that in which said bolts extend.

6. A strain insulator, comprising a body member provided with a tubular portion integral therewith and further provided with an annular recess encircling said tubular portion, a metallic cap provided with a portion engaging said body member and also engaging said tubular portion, mechanism engaging said cap for exerting upon said body member a pull in one direction, and mechanism including a member disposed within said annular recess for exerting upon said body member a pull in the opposite direction.

7. A strain insulator, comprising a body member of insulating material provided with a recess, a bolt extending partially through said body member and provided with an anchor disk having recesses, a plurality of bolts disposed within said recesses and thereby spaced from said anchor disk and said first-mentioned bolt, and means connected with said bolt for suspending said body member of insulating material and parts carried thereby.

8. A strain insulator, comprising a body member having a recess and also having a bolt hole, said recess and said bolt hole being axial relatively to said body member, a bolt fitting into said bolt hole and provided with an anchor plate fitting into said recess, a plurality of other bolts extending partially through said body member, and means for exerting tension upon said bolts.

9. A strain insulator, comprising a body member of insulating material provided with a recess, a single bolt engaging said body member and provided with an anchor disk disposed within said recess, said anchor disk being provided with recesses each having a boundary of substantially arcuate form, a plurality of bolts extending partially through said body member, said last-mentioned bolts extending centrally through said recesses of said anchor disk and thereby spaced from said anchor disk and from the bolt carrying the same, and means con-

nected with all of said bolts for mounting said body portion and parts carried thereby.

10. A strain insulator, comprising a body member provided with a recess and with a bolt hole merging into said recess, a bolt extending through said bolt hole and provided with an anchor plate, said anchor plate having generally the form of a disk provided with two recesses disposed upon opposite sides of said bolt, said anchor disk being further provided with a thickened portion co-axial with said bolt for the purpose of strengthening said anchor disk, and tension members extending partially through said body member and insulated from said bolt.

11. A strain insulator, comprising a body member of insulating material, an anchor ring disposed within said body member, a filling engaging said body member and covering said anchor ring for the purpose of insulating the latter, a cap mounted upon said body member and covering said filling, and mechanism engaging said cap for suspending said body member and parts carried by the same.

12. A strain insulator, comprising a body member of insulating material provided with a centrally disposed extension integral therewith, and further provided with an annular recess bounding said extension, and with a second recess disposed within said body member, and also provided with a hole extending through said extension and merging into said second recess disposed within said body member, and a plurality of holes extending through said body member and merging into said annular recess.

13. As an article of manufacture, a body member of insulating material provided with a recess and with a hole merging into said recess, said body member being further provided with an annular recess, and a plurality of holes merging into said annular recess.

In testimony whereof I have signed my name to this specification in the presence of two subscribing witnesses.

LOUIS STEINBERGER.
